CARPET KICKER

George A. Kochanowski, Chicago, Ill., assignor to Kinkead
Industries Incorporated, Chicago, Ill., a corporation of Illinois

Filed Nov. 4, 1966, Ser. No. 4,554

Term of patent 14 years

(Cl. D54—13)

FIG. 2 is a top plan view of the carpet kicker shown in FIG. 1;

FIG. 3 is a side view of the head portion of the carpet kicker shown in FIG. 1, fragmentarily shown for convenience of illustration.

FIG. 4 is a bottom view of the carpet kicker shown in FIG. 1; and

FIG. 5 is a front elevational view of the carpet kicker shown in FIG. 1.

I claim:

The ornamental design for a carpet kicker, substantially as shown.
